UNITED STATES PATENT OFFICE.

WILLIAM A. COPELAND, OF BROOKLINE, MASSACHUSETTS, ASSIGNOR TO THE PHONO-HARP COMPANY, OF EAST BOSTON, MASSACHUSETTS, A CORPORATION OF MAINE.

BASS ATTACHMENT FOR ZITHERS.

1,320,532.

Specification of Letters Patent.

Patented Nov. 4, 1919.

Application filed January 17, 1917, Serial No. 142,886. Renewed May 29, 1919. Serial No. 300,785.

To all whom it may concern:

Be it known that I, WILLIAM A. COPELAND, a citizen of the United States, residing at Brookline, in the county of Norfolk and 5 State of Massachusetts, have invented new and useful Improvements in Bass Attachments for Zithers (Case A,) of which the following is a specification.

This invention relates to zithers and has 10 for its object to provide a simple attachment for use in connection with groups of bass strings, so that an operator can cause a selected group to sound in accompaniment to a melody produced on a group of melody 15 strings.

On the drawing—

Figure 1 illustrates a zither equipped with an attachment embodying my invention.

Fig. 2 represents a section on the line 2—2 20 of Fig. 1.

Fig. 3 represents an enlarged section on the line 3—3 of Fig. 2 and is intended to show how the bridge wire is notched to insure that the strings, irrespective of their 25 dimensions, will be simultaneously engaged by the head of the associated striker.

The particular style and shape of the body portion of the zither to which my attachment is immaterial, and it is likewise immaterial whether the melody strings are plucked by the fingers of the player or 30 are caused to sound by the aid of hammers. As exemplifying one form of zither with which the attachment may be used, Fig. 1 35 illustrates a zither formed in the usual manner and having the apertured sounding board 5, which forms the upper wall of a hollow body. The melody strings, which are arranged to furnish either a diatonic 40 scale of any key or a chromatic scale, are indicated at 6. The chord strings are arranged in groups which are tuned to furnish the tonic, dominant and subdominant chords of a key, and an additional chord 45 such for example as bass *d*, *a*, *d*, and *f* if the tonic chord be in the key of *C*. In fact, in an instrument having the melody strings arranged in a chromatic scale, I may employ twelve groups of chord strings arranged as described in Letters Patent to 50 Marx No. 1,190,782, dated July 11, 1916. As indicated, however, there are four groups 7, 8, 9 and 10 of chord strings, each group consisting of a fundamental bass string, and 55 three additional strings to produce a triad.

The bridge wire 11, see Fig. 3, is provided with notches of different depths for the several chord strings, according to the respective cross dimensions thereof, so that the tops of the strings will be tangential to a 60 common plane for a purpose to be explained.

At the front end of the zither is the hand rest or guard 12, which is spaced by blocks 13 from, but which is secured by screws 14 to, the front end wall 15 of said zither. 65 This hand rest has at its upper edge a flange 16 overhanging the bridge wire but spaced above the strings, the under face of the flange being concave as shown in Fig. 2. This hand rest serves as a support for the 70 strikers for the groups of chord strings. Each striker is constructed and arranged to impinge upon all of the chord strings constituting one group, and, since there are four groups shown, I have accordingly illustrated four strikers. Each striker consists of a relatively stiff leaf spring 17 which is substantially equal in width to the space occupied by the associated four chord 75 strings, and which is so short that it will 80 not twist to any appreciable extent when lifted by one corner of its free end. One end of each such spring is secured to the under curved face of the flange 16 of the hand rest or guard 12, and its free end extends rearwardly longitudinally of the strings but is inclined thereto. On the under face of the free end of each spring is secured a head 18 by screws 19. The head in each case may be formed of wood or 85 metal, such, for example, as lead, but I prefer to construct it of relatively hard felt, of a width slightly greater than the group of strings therebeneath, to insure that the head will impinge upon all said strings. The 90 head is shown as triangular in section, to provide a beveled face 20 at an angle of about 40° or 45° to the plane of the strings, and a corner 21 for impingement on the strings. By reason of the arrangement of 95 the strings and the varying depths of the notches therefor in the bridge wire 11, the head will strike all of the strings of the group simultaneously and with the same degree of force. The heads are all preferably arranged in a row transversely of the 100 strings.

In operation, the operator from time to time inserts a thumb or finger under the beveled face of the head of one or another 110

of the strikers, lifts the free end of the 5
striker, and releases it, whereupon the resiliency of the spring and the momentum of the head will cause the head to strike all
of the strings of the associated group. Naturally, to prevent damping the strings, the heads, when at rest, are spaced above the strings.

Having thus explained the nature of my 10
said invention and described a way of making and using the same, although without attempting to set forth all of the forms in which it may be made or all of the modes of its use, what I claim is:—

- 15 1. The combination with a zither having melody strings and spaced groups of chord strings, of one striker for each group of chord strings, each striker consisting of a leaf spring substantially equal in width to 20
the associated group of strings, and having a head on the under side of its free end, said springs all extending longitudinally of the strings, and supporting means for attaching the fixed ends of said springs to said 25
zither with the heads in proximity to the strings, the free ends of said springs being exposed and unobstructed, in consequence of which each may be manually raised and then released.
- 30 2. The combination with a zither having melody strings and spaced groups of chord strings, and a hand rest or guard at the front end of said zither, of one striker for each group of chord strings, each striker 35
consisting of a leaf spring substantially equal in width to the associated group of strings, and having a head on the under side of its free end, said springs all extending longitudinally of the strings, and 40
means for securing the fixed ends of said springs to said hand rest or guard with the heads in proximity to the strings, the free

ends of said springs being exposed and unobstructed, in consequence of which each may be manually raised and then released. 45

3. The combination with a zither having melody strings and spaced groups of chord strings, and a bridge wire having notches of different depths as described for said strings according to their cross dimensions, 50
of one striker for each group of chord strings, each striker consisting of a leaf spring substantially equal in width to the associated group of strings, and having a head on the under side of its free end, said 55
springs all extending longitudinally of the strings, and supporting means for attaching the fixed ends of said springs to said zither with the heads in proximity to the strings, the free ends of said springs being exposed 60
and unobstructed, in consequence of which each may be manually raised and then released.

4. The combination with a zither having melody strings, and at one side thereof 65
spaced independent groups of chord strings, said zither having a support at the front end of the body thereof, of a plurality of strikers, one for each group of chord strings, each striker consisting of a leaf spring secured at its front end to the said support, and extending therefrom longitudinally of the associated strings, and a head affixed to the under side of the free end of such spring 70
and located in proximity to the associated 75
strings, and not less in width than the associated group of chord strings, the free ends of said strings being unobstructed to permit the free end thereof to be lifted and then released to strike all the chord strings of the 80
associated group.

In testimony whereof I have affixed my signature.

WILLIAM A. COPELAND.
